UNITED STATES PATENT OFFICE.

WELLS T. BARKER, OF LANSING, MICHIGAN.

DOUGH-ROLLING MACHINE.

1,094,966.

Specification of Letters Patent. Patented Apr. 28, 1914.

Application filed April 12, 1912. Serial No. 690,402.

To all whom it may concern:

Be it known that I, WELLS T. BARKER, a citizen of the United States of America, residing at Lansing, in the county of Ing-
ham and State of Michigan, have invented
certain new and useful Improvements in
Dough-Rolling Machines; and I do hereby
declare the following to be a full, clear, and
exact description of the invention, such as
will enable others skilled in the art to which
it appertains to make and use the same.

My invention relates to improvements in
dough rolling machines and its object is to
provide a machine that will form separate
masses of dough or other plastic material
into balls of uniform size, and to provide
the same with various new and useful fea-
tures hereinafter more fully described and
particularly pointed out in the claims.

My invention consists essentially of a
horizontally disposed rotating disk above
which are arranged spiral vertical walls and
vertically adjustable cap plates above the
walls and partially between the same, op-
posite the disk and spaced apart therefrom
forming a passage through which the mate-
rial is rolled, as will more fully appear by
reference to the accompanying drawings, in
which:—

Figure 1 is a vertical section representing
a device embodying my invention; Fig. 2 a
detail of the driving gear as shown at right
angles to Fig. 1; Fig. 3 an inverted plan
showing the spiral walls and under side of
the top plate; Fig. 4 is a detail in vertical
section through the disk, top plates and
hopper; and Fig. 5 is a detail in vertical
section through the joint of the top plate
and extension.

Like numbers refer to like parts in all of
the figures.

1 represents the driving shaft of the
machine.

2 represents a vertically disposed post or
standard on which is rotated a sleeve 3 con-
nected to the driving shaft by means of
gears 4 and 5 the form of gears shown be-
ing spiral gears. Supported upon the up-
per end of this sleeve is a horizontally dis-
posed disk 7 carried and rotated by the
sleeve.

8 is a non-rotating sleeve on the post 2 ver-
tically adjustable thereon by means of rods
9 secured to the sleeve at the lower end
and connected at the top by a yoke 10 in

which yoke is an adjusting screw 11 engag-
ing the end of the post whereby the sleeve
8 is adjustably supported by the screw.
Fixed on the lower end of this sleeve is a
top plate 12 arranged opposite the disk 7 60
and spaced apart therefrom more or less
according to the adjustment of the screw 11.
Surrounding this top plate is a spirally dis-
posed wall 14 preferably of sheet metal the
inner end of which is vertically reduced and 65
prolonged beneath the top plate as at 14^a
and extended to a point near the axis of
the machine. This spiral wall is arranged
close above the disk at the lower edge and
the margin of the top plate is close to the 70
inner side of this spiral wall throughout
the circumference of said plate. This wall
14—14^a is of such length as to form sub-
stantially two complete circuits and the
space between the circuits is progressively 75
reduced as it extends outward from the axis.
The periphery of the top plate is within the
inner circuit and is turned downward in a
curve close to the inner side of the wall 14.

An extension of this top plate 12^a is se-
cured to the same where it terminates in a
radial line, and both edges of this extension
are turned downward between the convolu-
tions of the spiral wall and its length is
substantially one half of a circuit. 80

Extending through the top plate is a
hopper 19 having a bottom opening through
the plate to receive and discharge the mate-
rial upon the rotating disk. This hopper is
located close to the inner surface of the in-
ner convolution 14^a of the wall 14 prefer-
ably near where it is reduced in vertical
width to extend under the top plate. A
spirally curved vertical wall is also pro-
vided between the top plate and the disk 95
which wall commences near the side of the
receiving opening nearest the axis of the
machine and extends thence spirally around
the axis gradually approaching the wall 14
and spaced apart therefrom. The wall 14 100
is carried on hangers 15 supported by a
spider 13 fixed on the post 2 being extended
upward to the top of the post and through
the upper part of the spider, the rods 9
slidably extend, to adjust the top plate ver-
tically. The wall 16 is also carried by the
spider on hangers 17 and 17^a the hangers 17
being intermediate the ends of the wall 16
and radially adjustable in a slot 18 in one
of the arms of the spider whereby the con- 105
110

vergence of the walls 14 and 16 may be adjusted and the end of the wall 16 permitted to spring away from the wall 14.

In operation the disk 7 is rotated by any suitable power applied to the pulley on the shaft 1. The dough or other plastic material divided into proper portions is dropped into the hopper 19 and falls upon the rotating disk and from thence is carried by the disk between the converging walls 14 and 16, the stationary top plate 12, and the rotating disk. This produces a rolling action on the material, compresses and rounds the same, which escaping from between the walls 14 and 16 is carried along the inner surface of the wall 14 by the disk and thence between the inner and outer convolutions of this wall and under the concave extension 12^a, being finally discharged from the narrowed end of this passage and off from the edge of the disk as indicated by the arrows being rolled and compressed into spherical shape by the machine.

What I claim is:—

1. A dough rolling machine, comprising a rotative disk, means for rotating the same, a spiral wall above the disk relatively fixed with respect to the rotative disk, means for rigidly supporting said wall, a top plate above the disk and spaced apart therefrom, and means for adjustably supporting said plate.

2. A dough rolling machine, comprising a rotative disk, means for rotating the same, a spiral wall above the disk and relatively fixed with respect to the disk and arranged to form a progressively reduced passage between its convolutions, means for rigidly supporting said wall, a top plate supported above the disk and having an opening to receive the material within the inner convolution of the wall, and means for rigidly supporting said top plate.

3. A dough roller, comprising a rotative disk, a spirally arranged wall above the disk and relatively fixed with respect to the latter and having one end near the axis of the disk and its other end near the periphery of the same and arranged to form a progressively reduced spiral passage between its convolutions, means for rigidly supporting said wall, a vertically adjustable top plate having its margin extending within the inner convolution of the wall, an extension of said plate extending between the overlapping convolutions of the wall and vertically adjustable means for supporting the plate and extension.

4. A dough rolling machine, comprising a horizontally disposed disk, means for rotating said disk, a fixed spiral wall above the disk beginning near the axis of the disk and extending to near the periphery thereof and also forming a progressively reduced passage between its convolutions, the inner end

of the wall being vertically reduced to extend under a top plate, a top plate above said inner end and having a downwardly turned margin close to one convolution of said wall, an extension of said top plate having both margins turned downward between the convolutions of said wall, vertically adjustable means for supporting the top plate, and fixed means for supporting said wall.

5. A dough rolling machine, comprising a rotative disk, a spirally arranged wall beginning near the axis of the disk at one end and having its convolutions spaced apart to form a spiral passage, said wall being relatively fixed with respect to the disk, means for rigidly supporting said wall, a hopper to deposit material within the inner convolution of said wall and a second curved wall beginning near the hopper and spaced apart from the first named wall to form a passage therebetween beginning at the hopper, a top plate, and means for supporting the top plate.

6. A dough rolling machine, comprising a horizontal rotative disk, a vertical post about which the disk rotates, means for rotating the disk, a fixed spiral wall above the disk, a spider supported by the post and connected to the wall to support the same, a sleeve vertically adjustable on the post and a top plate carried by the sleeve.

7. A dough rolling machine, comprising a horizontal and rotative disk, a post about which the disk rotates, a spiral wall above the disk, a spider attached to the post and having radiating arms, hangers extending downward from the arms and supporting said wall, a sleeve vertically adjustable on the post, a top plate carried by the sleeve, rods connected to the sleeve and extending upward through the spider, a yoke connecting the rods and a screw in the yoke engaging the end of the post to support the sleeve and plate.

8. A dough rolling machine, comprising a horizontal and rotative disk, a post about which the disk is rotative, a spiral wall above the disk spaced apart to form a tapered spiral channel, an inner curved wall spaced apart from the first named wall and within the first convolution thereof, a hopper to deposit material between said walls, a spider supported by the post and having radial arms, hangers connecting the arms and the outer wall, a top plate adjustably supported on the post and hangers in the arms supporting the inner wall and extending through openings in the top plate, one of which hangers is attached to said wall intermediate the ends thereof and radially adjustable in the arm of the spider.

9. The combination of a fixed vertical post, a disk rotatably mounted on said post, a top member sleeved on said post, means for holding the top member in fixed position relative to the disk and in spaced relation to the lat-

ter, a yoke supported on the vertical shaft, a spiral wall supported above the disk from said yoke and arranged to form a progressively reduced passage between its convolutions, the top member having an opening to permit passage of the material into the spiral passage, and means for rotating the disk.

10. The combination of a rotative disk, a top member fixedly supported above the disk in spaced relation thereto, a spiral wall supported over the disk relatively fixed with respect to the rotative disk with a portion of said wall arranged outside of the top member and with a portion projecting beneath said top member, the top member having an extension arranged over that portion of the spiral wall which does not project under the main top member, and means for rotating said disk.

20 11. A dough rolling machine comprising a

rotative disk, a spirally arranged wall beginning near the axis of the disk at one end and having its convolutions spaced apart to form a spiral passage, means for supporting said wall out of contact with said disk, and 25 relatively fixed with respect to the latter, a second curved wall spaced apart from the first named wall to form a passage therebetween and being yieldable at one end so that the second wall at one end may spring away 30 from the first-named wall, a top plate supported above the disk in spaced relation thereto, and means for supporting the top plate.

In testimony whereof I affix my signature 35 in presence of two witnesses.
